W. E. PINNEY ET AL

SHADE HANGER

Filed April 20, 1923

FIG. 1.

FIG. 2.

FIG. 3.

INVENTORS
Wallace E. Pinney &
Thomas Donahue
BY Joseph A. Miller
ATTORNEY

UNITED STATES PATENT OFFICE.

WALLACE E. PINNEY AND THOMAS DONAHUE, OF PROVIDENCE, RHODE ISLAND.

SHADE HANGER.

Application filed April 20, 1923. Serial No. 633,551.

To all whom it may concern:

Be it known that we, WALLACE E. PINNEY and THOMAS DONAHUE, citizens of the United States, residing at Providence, and

5 State of Rhode Island, have invented new and useful Improvements in Shade Hangers, of which the following is a specification.

This invention relates to certain new and useful improvements in shade-hangers, and 10 the primary object thereof is to provide improved means for securing or holding the brackets in position on a window frame.

A further object of the invention is to provide improved means for mounting inside 15 and outside shades, as well as inner and outer curtains, or as commonly styled over-drapes in position.

A still further object of the invention is to provide means for enabling adjustment of 20 the various curtain and shade supporting parts, and also to provide a structure of hanger which is of simple and economical construction.

The invention also aims to provide a hanger 25 of the type set forth which is secured in position without the use of driven fastening, and has still further and other objects which will be later set forth and manifested in the course of the following description.

30 In the drawings:—

Figure 1, is a front elevation showing the invention applied in position; Figure 2, is a detail perspective view of one of the brackets, and Figure 3, is a top plan view, 35 broken away, of Figure 2.

In proceeding in accordance with the present invention a lower L-shaped jaw 1 is employed having prongs or points 2 extending upwardly from its lower end or foot, the latter being provided with a depending member 3 formed to receive one of the shade pintles of the outer shade. The arm 4 of the jaw 1 is formed hollow and receives an inverted L-shaped member 5 therein, the 40 latter being adjustably secured to the arm 4 by means of screw 6. A vertically slidable jaw 7, slotted to receive the vertical part of the member 5 has its rear end corners each formed with a biting tooth 8, which latter are driven into the top of the window frame F by means of a vertical screw 9 which latter bears on the jaw 7. A horizontal body of strip form 10, slotted at 11 is secured to the vertical part of the member 5 by a screw 12. A substantially Z-shaped member 13 is 45 secured by a screw 14 to the strip 10 through

the slot 11 of the latter. The member 13 has its upper end 15 formed to engage on the top of the window frame F and has its lower end twisted at 16 and formed with a slot 17 to receive one of the pintles of the inner shade. From the above it will be seen that the members 13 can be easily adjusted to the lengths of the inner shades, and that the jaws 1 and 7 can be also adjusted to accommodate window frames of varying widths as to the top members thereof.

The outer end of the body 10, is provided with a pair of spaced inverted L-shaped clips 18 and 19, secured thereto in any suitable manner, the clips carrying short rods 20, and 21, respectively, and having screws 22 and 23, overlying the respective rods 20, and 21, so as to enable curtain supporting rods for inner and outer curtains, or over-drapes, to be firmly held onto the rods 20 and 21.

From the above it will be seen that in order to secure the brackets in position, the parts 15 and the jaws 7 are engaged with the top of the window frame, and the jaw 1 is then adjusted to engage the under side of the top of the window frame, whereupon the screw 6 is turned to rigidly connect the jaw 1 to the member 5. The set screw 9 is 50 then turned to drive the points 8 into the top of the window frame. It will be seen that the parts 5 and 13 can be adjusted by means of the screws 12 and 14 so as to occupy any desired position to accommodate the inner and outer shade rollers. The body 10 is thus supported by each of the parts 5 and 13, the latter parts in turn being supported against downward movement by their engagement with the top of the window frame.

The device thus constitutes but three major parts namely brackets 5 and 13 and body 10 which connects the brackets.

Having thus described our invention, what we claim as new and desire to secure by Letters Patent is:—

1. In a shade and curtain hanger, a bracket including a horizontal slotted body, L-shaped clips at the outer end of the body having vertical screws, curtain pole supporting rods connected to the clips and body and underlying the screws, a Z-shaped member having its upper end formed to engage on top of the window frame and having its lower end formed to receive a shade pindle, a screw engaged in the body slot to adjustably secure the Z-member thereto, an

- inverted L-shaped member having a vertical set screw at its top, a jaw slotted to adjustably receive the L-member and engaged by the last named set screw and having points 5 to bite into the top of the window frame, a set screw in the body slot for adjustably securing the L-member to the body, and an L-shaped jaw having a socket to receive the lower end of the L-member, a screw for securing 10 the socket to the L-member, a pintle bracket depending from the foot of the L-jaw, and upwardly extending points carried by the foot of the L-jaw to engage in the under side of the top member of the window frame.
2. In a shade and curtain hanger, a bracket including a horizontal body member, a shade supporting member adjustably carried by the body member and having a part 20 formed to engage on top of the window frame, an L-jaw having a shade pintle engaging part and having points formed to engage in the under side of the top of the window frame, an L-member adjustably secured to the body member and to the L-jaw, a slotted jaw slidable on the L-member and having points formed to engage the top of the window frame, and means carried by the L-member to engage the last named jaw to 25 adjustably force the points thereof into the window frame.
3. In a shade hanger, a bracket including a body, a pair of spaced shade roller supporting members each adjustably secured to the body, one of said members having a part 35 engaging the top face of the top of the window frame, and means to secure the other of said members to the window frame including parts engaged with the top and bottom faces of the top of the window frame.
4. In a shade and curtain hanger, a body having curtain pole supporting means on one end, a pair of independent shade roller supporting members on the opposite end of the body, means to adjustably connect said members to the body, one of said members having a part engaging the top face of the top of the window frame, and means to secure the other of the shade roller supporting members to the window frame by engagement with the upper and lower faces of the top thereof.

In testimony whereof we have signed our names to this specification in the presence of two subscribing witnesses.

WALLACE E. PINNEY.
THOMAS DONAHUE.
